UNITED STATES PATENT OFFICE

HARRY DIXSON, OF PELLA, IOWA, ASSIGNOR TO ROLSCREEN COMPANY, OF PELLA, IOWA

ROLL SCREEN LATCH

Application filed July 29, 1929. Serial No. 381,730.

The object of my invention is to provide a latch device for roll screens of simple, durable and comparatively inexpensive construction.

5 More particularly, it is my object to provide a latch device adapted to be telescopically mounted on a track of a rolling window screen and capable of slidable movement thereon, whereby to provide proper 10 adjustment of the latch element relative to the track and at the same time to provide means whereby the latch member may be locked relative to the track after initial adjustment.

15 Still a further object is to provide a latch element adapted to engage the lower marginal ledge of a rolling window screen for holding the screen in its withdrawn position and against the normal tendency of the screen 20 to move upwardly or to be retracted, the latch element being adjustable so that irrespective of the position of the window sill the latch element may always be brought into engagement with the window sill and as result 25 thereof the ledge of the rolling window screen will always come in contact with the window sill, insuring a fly-tight connection.

Still a further object is to provide a pair 30 of members, one of which is slidably mounted upon the other, each of the members being provided with a plurality of spaced elongated openings, the elongated openings being so arranged that at least one of the openings of one of the members will register 35 with one of the openings of one of the other members at all times.

Still another object is to provide a plurality of openings in one member and a plurality of openings in another member, the 40 openings in one member and the openings in the other member being spaced different distances apart, whereby slidable movement of one member upon the other will cause at least one of the openings to have full registration 45 with an opening of the other member, to the end that when a nail or the like is driven through the openings in full registration with each other, the parts will be permanently and fixedly held relative to each other.

50 It may be here mentioned that from a prac-

tical installation standpoint, it is desirable that the latch member to retain a rolling window screen in its withdrawn position be located against the sill of the window and yet carried by the track proper, and in order 55 so to do, I provide a latch element, which is of substantially the construction shown in Letters Patent, No. 1,715,858, issued June 4, 1929, to the Rolscreen Company, as assignee, which device is capable of adjustment of 60 the finest degree or adjustment of a great variance, such adjustment being accomplished by a plurality of openings formed in the latch member and the member upon which the latch is slidably mounted. 65

With these and other objects in view, my invention consists in the construction, arrangement and combination of the various parts of my roll screen latch, whereby the objects contemplated are attained, as herein-after more fully set forth, pointed out in my claims, and illustrated in the accompanying drawings, in which:

Figure 1 is a plan view of a portion of a window frame together with a lower portion 75 of a rolling window screen with my improved latch installed thereon.

Figure 2 is a sectional view taken on the line 2—2 of Figure 1.

Figure 3 is an elevation view of a portion 80 of a roll screen track with my latch mounted thereon.

Figure 4 is a similar view with the latch shown in a different position; and

Figure 5 is a sectional view taken on the 85 line 5—5 of Figure 3.

In the accompanying drawings, I have used the reference character A to indicate generally a window frame, which is provided with a pair of side jambs 10 and a sill 12. The upper portion of the window frame as well as the upper portion of the roll screen assembly is not here illustrated. 90

For purposes of reference, however, I refer 95 to my Letters Patent issued August 7, 1928, No. 1,680,092, as disclosing the type of rolling window screen for which my present device is applicable.

The roll screen assembly includes a screen 100

14 having a binder 16 thereon, provided with an in-turned or lower ledge 18.

The latch element that I provide is adapted to coact with the ledge 18 for normally holding the screen in its withdrawn position.

The side edges of the screen 14 are adapted to travel in guide tracks 20, which are mounted on the side jambs 10 of the window frame A.

10 Each guide track includes a tubular portion 22 and a flat attaching flange 24. The flat attaching flange 24 is adapted to rest against the side jambs 10 and to be secured thereto by screws or the like 27. The screws 15 project through elongated slots 29 whereby adjustment of the tracks toward or from each other may be accomplished.

My latch element includes a resilient member B arranged in circumscribing relationship to the track 20.

20 Each element B includes a tubular portion 26 adapted to closely overlie a tubular portion 22 of the track 20. A pair of flat spaced flanges 28 are included in the element B and between these flanges 28 is received a flat attaching flange 24, all as clearly illustrated in Figure 5 of the drawings.

25 A resilient projection 30 is carried by the body of the latch element, and a lug 32 is formed thereon which coacts with the lower ledge 18 of the binder 16.

30 In order to provide for proper adjustment of the latch element B upon the track 20, I provide a series of spaced openings 34, upon the flat attaching flange 24 of the track 20. Through the two flanges 28 of each latch element B, I likewise provide a series of openings 36.

35 The openings 34 are spaced a greater distance apart than are the openings 36, the purpose of which will be hereinafter more fully set forth.

40 In order to hold the latch element B in adjusted position, I employ a nail or the like 38, which may be driven through one of the openings in the latch element B and through one of the openings in the track 20.

45 It may be here mentioned that when the track is slightly short of the required height, then the latch element may be moved downwardly, so that its lower end projects down below the lower end of the track, as clearly illustrated in Figure 4 of the drawings. In such case, the nail 38 retains the track and 55 latch in proper position.

50 In Figure 3 of the drawings, I have shown the track as being slightly too long, and in such event, it is cut off on the job, and thereafter the latch element serves as the lower end 60 finish for the installation of the track.

55 By providing the openings 34 and 36 in different spaced distances, I am able to have at least one opening of the latch element coincide or register with at least one opening 65 of the track member at all times.

It will be noted from the drawings that some of the openings in the latch element B are in partial register with the openings in the track member, while one opening, to-wit, the opening C is in full registration.

70 In the practical installation of my device, the track is first cut to substantially the proper length and the latch element B is slid upon the track adjacent the series of openings therein provided. The latch is moved to its lowermost position, so that its lower end touches the sill and thereafter a nail 38 is driven through one of the openings, which is in registration with the opening in the track 20.

75 It will be noted that the openings are elongated crosswise of the attaching flange, and the purpose of this is to permit the entire track and the latch carried thereby to be adjusted towards or from the track on the other side of the window frame.

80 My latch is one that has been proven practical in actual use and a great many of them are now in use.

85 Some changes may be made in the arrangement and construction of the parts of my roll screen latch, without departing from the real spirit and purpose of my invention, and it is my intention to cover by my claims, any modified forms of structure or use of mechanical equivalents, which may be reasonably included within their scope.

90 I claim as my invention:

1. In combination with a guide track having a flat attaching flange, a latch for a rolling window screen comprising a resilient member slidably mounted upon said track in circumscribing relation thereto, the attaching flange of said track having a plurality of spaced openings therein, said resilient member having a plurality of spaced openings therein adapted during its slidable movement to have at least one of its openings in register with one of the openings in said track, whereby a fastening element may be 100 projected therethrough for locking said resilient member relative to the track.

105 2. In combination with a guide track having a flat attaching flange, a latch for a rolling window screen comprising a resilient member slidably mounted upon said track in circumscribing relation thereto, the attaching flange of said track having a plurality of spaced openings therein, said resilient member having a plurality of spaced openings 110 therein adapted during its slidable movement to have at least one of its openings in register with one of the openings in said track, whereby a fastening element may be projected therethrough for locking said resilient member relative to the track, said openings in the track being elongated in a direction crosswise of the attaching flange.

115 3. In combination with a guide track having a flat attaching flange, a latch for a 120

rolling window screen comprising a resilient member slidably mounted upon said track in circumscribing relation thereto, the attaching flange of said track having a plurality of spaced openings therein, said resilient member having a plurality of spaced openings therein adapted during its slidable movement to have at least one of its openings in register with one of the openings in said track, whereby a fastening element may be projected therethrough for locking said resilient member relative to the track, the openings in the track being spaced a different distance apart than the openings in said resilient member, whereby substantially only one opening in said member will be in register with one opening in said track.

4. In combination with a guide track having a plurality of spaced openings, a latch element carried by said track in telescopic relationship and having a plurality of openings, the openings in said members being so arranged that during movement of one member relative to the other at least one opening in each series of openings is brought into full registration with one opening in the other series.

5. In combination with a guide track having a plurality of spaced openings, a latch element carried by said track and having a plurality of openings, the openings in said members being so arranged that during movement of one member relative to the other at least one opening in each series of openings is brought into full registration with one opening in the other series.

Des Moines, Iowa, June 26, 1929.

HARRY DIXSON.
